UNITED STATES PATENT OFFICE.

ALBERT AICHELE, OF BADEN, SWITZERLAND, ASSIGNOR TO AKTIENGESELLSCHAFT
BROWN BOVERI & CIE., OF BADEN, SWITZERLAND.

PIVOTAL JOINT BETWEEN AN ALTERNATING-CURRENT ELECTROMAGNET AND ITS ARMATURE.

1,255,121.

Specification of Letters Patent.

Patented Feb. 5, 1918.

Application filed December 30, 1916. Serial No. 139,907.

To all whom it may concern:

Be it known that I, ALBERT AICHELE, a citizen of the Swiss Republic, residing at No. 10 Wiesenstrasse, in the town of Baden, 5 in Switzerland, have invented certain new and useful Improvements in Pivotal Joints Between an Alternating-Current Electromagnet and Its Armature, of which the following is a specification.

10 This invention relates to alternating current electromagnets of the type wherein the armature is pivoted to the frame or body of the magnet, and the improvements have for their object to provide an improved 15 pivotal connection between the alternating current electromagnet and its armature in such a case.

In the construction hitherto employed the pivot pin of the armature has a slight 20 amount of "play" in its bearings which may be due to the manufacture or be the result of wear, and this "play" causes a buzzing noise in the operation of the magnet.

This buzzing noise is prevented by the 25 present invention which consists in pressing the pivot pin of the armature firmly against its bearings in the fixed body of the magnet by means of endless elastic devices placed under tension. By this means the vibration 30 that produces the buzzing is either entirely prevented or at least is limited to a few rare occurrences.

The simplest way of carrying this invention into effect is to use an endless elastic 35 band, for instance an endless rubber band or a helical spring formed into a closed loop, which is looped under tension around both the pivot pin of the armature and a projection of the body of the magnet.

40 An embodiment of this invention is illustrated by way of example in the accompanying drawings in which Figures 1 and 2 are respectively a side elevation and a vertical section of an electromagnet with a pivoted 45 armature.

Fig. 3 shows a detail.

In this example:—*a* is the body of the electromagnet, and *b* is the armature pivoted to it. *c* are the cheeks of the electromagnet; 50 they are formed at their lower ends with notches *d* that serve as bearings for the pivot pin *e* of the armature *b*. *f* are two closed loops each composed of an endless helical spring. *g* are projections located one

on each of the two sides of the magnet body 55 *a*. The spring loops *f* are looped under tension around the ends of the pivot pin *e* and the projections *g*, and they have thus a constant tendency to keep the pivot pin *e* well up against its bearings *d* in the magnet 60 body.

In order to prevent an accidental disengagement of the springs *f* from their seats *d* and *g*, and also for the purpose of preventing the armature *b* from dropping in case of 65 a spring *f* breaking when no current is passing through the magnet, plates *h* are fixed to the projections *g* by means of screws *i*. These plates *h* which are shown in Figs. 2 and 3, are omitted in Fig. 1 for the sake of 70 clearness.

The improved arrangement has the advantage of allowing the armature *b* to be very easily removed from and replaced on the magnet *a*. In order to disconnect the 75 armature from the magnet it is sufficient to unscrew the screws *i*, remove the plates *h* and then slip the springs *f* off one or other or both of the parts *e* and *g*.

What I claim is:—

80

1. In an alternating current electromagnet having an armature pivoted thereto, the combination of a bearing notch in said magnet, a pivot member on said armature cooperating with said bearing notch to form 85 the pivotal connection between said armature and said magnet, and an endless elastic member engaging said armature and said magnet and having a constant tendency to keep said pivot member pressed into said bearing notch.

2. In an alternating current electromagnet having an armature pivoted thereto, the combination of a bearing notch in said magnet, a pivot member on said armature cooperating with said bearing notch to form 95 the pivotal connection between said armature and said magnet, and an endless elastic member looped around said magnet and said pivot member and having a constant tendency to keep said pivot member pressed into said bearing notch.

3. In an alternating current electromagnet having an armature pivoted thereto, the combination of a bearing notch in said magnet, a projection on said magnet located inward of said bearing notch, a pivot member 105 on said armature cooperating with said bear-

ing notch to form the pivotal connection between said armature and said magnet, and an elastic closed loop composed of a helical spring looped under tension around said projection and said pivot member so as to have a constant tendency to press said pivot member in said bearing notch.

4. In an alternating current electromagnet having an armature pivoted thereto, the combination of a bearing notch in said magnet, a projection on said magnet located inward of said bearing notch, a pivot member on said armature coöperating with said bearing notch to form the pivotal connection between said armature and said magnet, an elastic closed loop composed of a helical spring looped under tension around said

projection and said pivot member so as to have a constant tendency to press said pivot member in said bearing notch, and a plate-like member formed with a hole for engaging said projection and a hole for engaging said pivot member, located externally of said elastic closed loop, and means for retaining said plate-like member in place, whereby 20 said elastic closed loop is prevented from slipping off said projection and said pivot member, and whereby also said armature is kept from falling away from said magnet in case of said elastic closed loop breaking. 25

In testimony whereof I have signed my name to this specification.

ALBERT AICHELE.
